ATTORNEY.

UNITED STATES PATENT OFFICE.

FREDERICK ROTTI, OF ELIZABETH, NEW JERSEY.

WINDOW FLOWER-STAND.

1,177,449.

Specification of Letters Patent. Patented Mar. 28, 1916.

Application filed July 3, 1915. Serial No. 37,820.

To all whom it may concern:

Be it known that I, FREDERICK ROTTI, a citizen of the United States, residing at Elizabeth, county of Union, and State of New Jersey, have invented certain new and useful Improvements in Window Flower-Stands, of which the following is a specification, reference being had to the accompanying drawings.

10 This invention relates to certain new and useful improvements relative to window flower stands and has for its object to provide one which may be readily attached or detached from the window and can be folded into a compact form so as to require little space when stored away.

Another object of the invention is to provide a window flower stand which may be adjusted to varying lengths to suit windows 20 of different widths.

Another object is to provide a window flower stand which may be adjusted outwardly, with respect to the window, so as to make the stand wide or narrow according to the requirements of flower pots and flower boxes.

It is a known fact that window stands heretofore used have been made up at the factory in standard widths and any window 30 between or above these widths required a special order, which always entailed not only a delay in the customer receiving his desired stand but also an additional expense. This objection is overcome by the 35 use of my stand which may be adjusted to a plurality of different widths and will accomplish the desired result when either in its minimum or maximum widths.

To these ends the invention consists in 40 the features hereinafter described and set forth in the claims.

The various features of the invention will be readily understood from an inspection of the accompanying drawings and the following detailed description of the device 45 illustrated therein.

Like reference numerals designate similar parts throughout the several views.

In the drawings Figure 1 is a front elevation of the stand showing it applied to a window opening, Fig. 2 is a cross section of Fig. 1, Fig. 3 is a cross section on line 3—3 of Fig. 1 showing the manner in which the

parts are securely held in any desired adjustment, Fig. 4 is a sectional view on line 4—4 in Fig. 3.

Reference character A designates a window sill of ordinary construction to which the supporting member may be secured. This support is made adjustable by having 60 a channel bar 1 with a row of threaded holes 1' in which a solid bar 3 is fastened and which bar is rigidly secured to the sill A by suitable fastening means as shown at 2. Solid bar 3 is held by means of a wing-screw 4 in the channel bar 1 as shown in Fig. 3. Arranged beneath this support and secured to the outer end thereof, a suitable brace 6 extends downwardly and inwardly therefrom and is attached to the wall by 70 any desired means as shown at 7. The upper end of said brace 6 fits into channel bar 1 and is fastened by a wing-screw 5 to the channel bar 1. The brace 6 as shown in Fig. 3 could be so adjusted as to fit any 75 wall thickness by simply sliding the brace into the required position, remove the wing-screw 5, and insert the same into the threaded hole 1', and fasten the same.

A member 8 is riveted at the outer end 80 to the channel bar 1 and extends upwardly, as shown in Figs. 2 and 3. Pivotaly secured to 8 through the opening 9 is an extensible member 10 which consists of a plurality of crossed bars pivoted at their intersecting points and also pivotally connected together at each end to the adjacent bar thereby constituting a lazy tong construction. This member 10 forms the vertical wall of the window flower stand and can 85 be adjusted to any desired width. At the ends of the member 10 are two vertical rods 11—12 which are pivotally secured to the upper and lower end of the said member by means of a pin and slot connection and 90 slidably connected thereto at the upper and lower end by means of a pin and slot connection 13 and 14. Adjustable rods 15 and 16 are secured to each vertical rod intermediate its ends and is adapted to be attached to the window frame B at its opposite end thereby sustaining the frame in its upright position. From this construction it will follow that when the rod 16 is mounted on the window frame the extensible member 105 may be adjusted without any further

adjustment of the rod 16. The rods 15 and 16 are securely held in any desired adjusted position by means of screws 17 which can be set in any of the threaded holes 18 to allow adjustment.

When the window flower stand as above described has been applied to a window all that will be necessary to complete the same is a board *b*, which will be laid across the support as shown in Figs. 1 and 2.

It will of course be understood that while the preferred embodiment of the invention has been described herein, departures therefrom as to detailed constructions may be resorted to without departing from the spirit or scope of the invention.

What I claim is:

1. A window flower stand comprising a plurality of longitudinally adjustable supports spaced apart and adapted to be secured at one end to a window sill, a plate on said supports, an extensible member secured to said supports, said extensible member comprising bars pivoted together, and end bars having adjusting slots at each end adjustably connected with certain of said bars, and longitudinally adjustable brace members connected to the respective end bars

and adapted to be secured to the window sill.

2. A window flower stand comprising an adjustable support secured to the window sill, a board on said support, said support having an end portion extending in a vertical direction, an extensible member secured to said end portion, an adjustable member having connection with the extensible member adjacent each end thereof and adapted to be secured to the window frame thereby sustaining the extensible member in proper position.

3. A window flower stand comprising a channel bar, a rod adjustably secured therein and adapted to be secured at one end to a window sill, a brace secured to the outer end of said bar, a plate mounted on the channel bar, an extensible member having connection with said bar and means for sustaining said member in an upright position.

In testimony whereof I affix my signature in presence of two witnesses.

FREDERICK ROTTI.
